G. G. HERMANCE.
WATER WHEEL.

Patented Sept. 30, 1834.

Sept. 30, 1834

March 3. Holmanance. County of Green, & State of New York

8423X

Letters Patent.

The schedule referred to in these Letters Patent and making part of the same, containing a description in the words of the said Garrett G. Holmanance, himself of his improvement in the construction of water wheels to turn or propel all kinds of Machinery.

To all to whom these presents shall come.

Be it known that I, Garrett G. Holmanance, of the Town of Lonsackie, in the County of Green, and State of New York, have invented a novel and useful improvement in the construction of water wheels for propelling all kinds of machinery, rail road cars, boats or vessels &c. And that the following is a full and exact description of the construction and operation of the said water wheel as invented or improved by me.

The wheel revolves in a hollow cylinder (to be hereafter described) and is made of solid metal, except the open spaces; the sliding bearing and packing, having a shaft projecting from each end to any length required; or it may be made with holes to receive the end of the shaft. The wheel must be turned perfectly true, with grooves on the sides for packing. Open spaces are cut into the wheel from the periphery towards the center, in which slide the bearing; they are six or more in number, at equal distances apart, and in a straight line across the center; they are one fourth of the diameter of the wheel in depth, that is, from the periphery towards the center their sides to be perfectly parallel, and smooth so as to offer as little impediment as possible, to the sliding of the bearing; the center of the wheel must be open. Six eight or ten holes are bored through the body of the wheel, connecting in direct line, the opposite open spaces, through each of these holes

paper-wheels, the object of which is to give motion to the valves. The valves are made to slide into the open spaces, above described, perfectly airtight, of the same width of the wheel, and the length of the depth of the open spaces, above described, perfectly airtight, these interedges to be packed airtight. The hollow cylinder, which surrounds the wheel, is made of cast iron bored out perfectly true and smooth, of the same width of the wheel, and its inner diameter one fourth larger. Circular plates of cast iron turned perfectly flat, are screwed on the ends of the cylinder with hole in the centres through which passes the shaft of the wheel. There are two metallic blocks attached to the inside of the cylinder the faces of which are straight, and at one point touch the periphery of the wheel, they are so placed as that, while one valve passes under one block, the opposite valve passes from under the other. The object of these is to push in and out the valves, that is, as the wheel revolves, the valves successively come in contact with the block which need push them in and out, as the blocks touch the periphery, the wheel at opposite points, and as there is a rod which passes through the wheel from one valve to the other, the opposite valve must be pushed out so far as to make its end touch the inner surface, the cylinder, a hole is cut perpendicular through the cylinder, and passing also through one of the blocks to admit the water on the one as the wheel revolves, a perpendicular pipe connects this hole with a reservoir of water, when the wheel is made to revolve or revolve the other way, a similar hole and pipe is made on the side of the cylinder passing through the other block. These holes are provided with a stopcock to shut off the water when required to stop the wheel at the bottom of the cylinder there is a hole to let off the water after it has operated.

Operation. - when the wheel is made when there is a sufficient head of water, the water descends from the reservoir through the pipe onto the valves, and by its pressure causes them to revolve in such a manner as to pass the lot off hole, where the water

is discharged. But when the supply of water is small, and it is desired to increase the power of the wheel, the water descends from the reservoir onto the valves of the wheel, as before described, and after it passes from the let off hole into the reservoir, it is forced out by a forcing pump, which is worked by the wheel, and at the same time, produces a vacuum under the valves. When it is applied to boats or railroad cars, the water is raised into a reservoir by steam or manual power; it then descends thro' the perpendicular pipe on the valves as before described, and out through the let off hole into the reservoir, and then forced up into the reservoir above mentioned, at the same time producing a vacuum under the valves.

The dimensions of the wheel and its several parts can be varied according to the power required, and the fancy of the builder, provided the principle be retained.

What I claim as new, and as my invention and for which such letters patent, is the construction of the described water wheel, the principle of hydrostatic pressure as applied to water wheels, and the producing a vacuum under the valves of the wheel, by forcing pumps, and also the principle of propelling railroad cars, and boats or vessels, by water power.

In testimony that the above is a full and exact description of the construction and operation of my invention I have hereunto subscribed my name this 27th day of December, in the year of our Lord 1834.
